UNITED STATES PATENT OFFICE.

EMIL LUCKE, OF PORTLAND, OREGON.

POLISHED PLATE-GLASS LENS.

1,208,807.

Specification of Letters Patent. Patented Dec. 19, 1916.

Application filed April 19, 1916. Serial No. 92,147.

To all whom it may concern:

Be it known that I, EMIL LUCKE, residing at Portland, in the county of Multnomah and State of Oregon, have invented 5 certain new and useful Improvements in Polished Plate-Glass Lenses, of which the following is a specification.

My invention relates to improvements in polished plate glass lenses for automobile 10 lights and the same has been particularly designed for use as a dimmer to prevent the rays of light emanating from the lamp from blinding pedestrians or others approaching from in front and to this end the 15 invention resides in providing the lens with an upper semi-circle of ground glass and a depending central "tab" of ground glass to cut off direct transmission of the light from the bulb or illuminant, the lower half 20 of the lens being of transparent glass and provided with miter cuts for dispersion purposes.

The invention also resides in those novel 25 features of construction hereinafter fully described and pointed out in the appended claims, reference being had to the accompanying drawings, in which:

Figure 1 is a front or face view of a lens 30 constructed in accordance with the invention. Fig. 2 is a vertical section on the line 2-2 of Fig. 1. Fig. 3 is a horizontal section on the line 3-3 of Fig. 1. Fig. 4 is a view similar to Fig. 1 of a slight modification. Fig. 5 is a cross section on the line 5-5 of 35 Fig. 4. Fig. 6 is a face view of a further modification. Fig. 7 is a horizontal section on the line 7-7 of Fig. 6. Fig. 8 is a vertical section on the line 8-8 of Fig. 6.

In the drawing, in which like numerals 40 and letters of reference indicate like parts in all of the figures, the lens 6 is preferably of the convex type and is provided with a rim or flange portion 7 having notches 5 at intervals, by means of which the lens can 45 be fixedly located in place. The upper half of the lens is ground to form a surface 1 that merges with a depending semi-circular ground surface 2 in the form of a "tab" to prevent direct passage of the rays from the

light source or bulb. The lower half of 50 the lenses is clear, as at 3, and is provided with suitably arranged vertical miter cuts 4 to increase the light on the ground, by dispersion.

In the forms shown in Figs. 4 and 5, the 55 "tab" 2 is of transparent glass and the miter cuts 4 are on the inner side of the glass instead of on the outer side as in the forms shown in Figs. 1 and 2. As in the form shown in Figs. 6, 7 and 8, the ground 60 portion of the glass may be the lower half and the miter cut clear portion on the upper half of the lenses. I desire it understood that in either form of the invention 65 the lenses may be used with the ground portion down and the clear portion up or the clear portion down and the ground portion up, as may be found desirable, and depending upon whether or not the lamp is a gas lamp or an electric lamp, and depending 70 upon the nature of the reflectors within the lamp.

From the foregoing description, taken in connection with the accompanying drawing, it is thought the complete construction and 75 advantages of my invention will be readily understood by those skilled in the art to which the invention relates.

What I claim is:

1. A lens, the upper half of which is 80 ground and provided with a tab portion at the center also of ground surface, the lower half, except the tab, being clear and provided with vertically extending parallel miter cuts.

2. A lens comprising a plate, one-half of 85 which is ground and the other half clear, the clear half being provided with parallel light distributing miter cuts.

3. A lens, the upper half of which is 90 ground and provided with a tab portion at the center also of ground surface, the lower half, except the tab, being clear and provided with vertically extending parallel miter cuts, said lens also including an annular rim portion having notches substantially as shown and for the purposes described.

4. A lens comprising a body, a portion of which is ground and the remaining portion is provided with alternating clear surfaces and parallel light distributing grooves.
5. A lens comprising a sheet glass body approximately one-half of which is ground to form a continuous translucent portion,

and the remaining part of said body being provided with parallel vertically extended light distributing undulations or grooves. 10

EMIL LUCKE.
